UNITED STATES PATENT OFFICE.

GEORGE CLAUSING, OF PORTSMOUTH, OHIO. ASSIGNOR TO THE VULCAN BOX TOE
PROCESS CO., OF PORTSMOUTH, OHIO, A CORPORATION OF OHIO.

LAST.

1,107,656.

Specification of Letters Patent. Patented Aug. 18, 1914.

Application filed February 12, 1914. Serial No. 818,354.

To all whom it may concern:

Be it known that I, GEORGE CLAUSING, a citizen of the United States, residing in the city of Portsmouth, in the county of Scioto and State of Ohio, have invented certain new and useful improvements in Lasts, (Case 1,) of which the following is a specification.

The object of the invention is to produce a simple, strong and practical last which can be broken or flexed to facilitate the removal of the last from the shoe and so that the shoe will not be marred, broken or pulled out of shape during the removal of the last from the shoe.

Another object of the invention is to construct a last so that the same will withstand the rough usage to which such lasts are subjected when in the lasting machine and so that its parts will maintain their proper positions relative to each other during such use.

According to the present invention the last is constructed so that it it comprises a forward or toe part and a rear or heel part connected together by a longitudinally and vertically extending plate in a manner that permits the heel part, for example, to be moved upwardly and forwardly relative to the toe part when it is desired to move the heel part from the extended position shown in full lines in Figure 1 to the broken position which is indicated by the dotted lines in the same figure. In the construction shown in the drawings, this connecting plate is secured to the toe part and is provided with a pair of slots through which pass pins or rivets that are comprised in the heel part. In order to maintain the heel part and toe part in extended position relative to each other, there is provided a spring means which engages the said connecting plate in a manner to normally tend to force said last parts toward extended or unbroken position relative to each other.

As showing a specific embodiment of the invention, reference is made to the drawings forming part of this specification, and in which,—

Figs 1 is a vertically and longitudinally extending sectional view of the last showing the parts in extended or unbroken position. In this figure the broken lines indicate the position of the heel part when the

heel and toe parts are in broken or shortened position. Fig. 2 is a plan view partially in section. This is a view taken on the line 2—2 of Fig. 1 looking in the direction of the arrows. Fig. 3 is a view taken on the broken line 3—3 of Fig. 1 looking in the direction of the arrows.

The last designated by A comprises the fore or toe-part B and the rear or heel part C. In the construction of the last these parts are preferably formed from a single piece of wood and are integrally connected together. They are subsequently separated by transversely sawing along the line b—b and a wedge-shaped portion b, c, d, is removed in order to permit the heel part to assume the position indicated by the broken line in Fig. 1. The last parts are then provided with the longitudinally and vertically extending saw-cuts or slots e and f for receiving therein the longitudinally and vertically extending connecting plate D. This connecting plate is provided at its forward end with the two circular pin-receiving holes g—g, and at its rear portion with the substantially upright slot h and with the slot i which extends upwardly and forwardly. This plate is also provided with the rearwardly extending projection or nose k. This plate D is rigidly secured directly to the toe-part of the last by the transversely extending pins or rivets g' which pass through the pin-receiving holes g—g. In the heel part of the last there are also a pair of transversely extending pins or rivets g'' which pass through the slots above referred to.

In the heel part of the last there is a bored opening z for receiving the spring means E. This bored opening extends upwardly and forwardly and the spring means which is located therein comprises the compression spring e' and the cap e''. The cap engages the rearwardly extending nose or projection k on the connecting plate while the lower end of the spring 100 rests against the plug l' which fits into the bored opening l. The heel part is also provided with the metal plate f that is secured in place by any suitable means such as the screws f'. This plate serves not only to turn the ends of the nails which are driven thereagainst during the process of lasting but it also serves as a means to resist the

plug from being forced outwardly by the spring thus always insuring the retaining of the plug in place.

From an inspection of Fig. 1 it will be noted that the forward lower portion of the heel part of the last directly engages the rear lower portion of the toe part of the last and that there is thus a substantial bearing surface between said heel and toe parts when the last is being used. It will also be noted that the lower pin or rivet g'' which is in the heel part of the last directly engages that portion of the plate which defines the lower extremity of the slot h when the heel and toe parts are in extended position. It will also be noted that the upper rivet or pin g'' directly engages that portion of the connecting plate which defines the lower rear portion of the slot i when said parts are in extended position. These pins $g''-g''$ and the slots in the plate are, therefore, arranged so that the pins and plate coöperate to limit the downward movement of the heel part of the last as well as the rearward movement of the upper portion of the heel part of the last and said pins and slotted portions of the plate are also arranged so that when the heel and toe parts are in extended position the said last parts will directly seat against each other.

The improvements herein set forth are not limited to the precise construction and arrangement shown and described and may be embodied in various forms and modifications without departing from the spirit and scope of the invention.

I claim as my invention:

1. A last having a heel part and a toe part which are separated by a transversely extending saw cut that extends from the top to the bottom of the last, said parts having longitudinally and vertically extending saw cuts and being connected together by a vertically and longitudinally extending plate that is located in the longitudinally and vertically extending saw cuts in said parts, said plate being rigidly secured to the toe part by transversely extending rivets or pins and being provided with a rearwardly extending nose and a pair of pin-receiving slots, the heel part being provided with a spring means which engages the nose on the plate for forcing said toe and heel parts toward unbroken or extended position, the heel part also being provided with rivets or pins that extend through said slots in the plate, which pins are arranged so that when the last parts are in extended position the pins are located in the lower portion of the slots.

2. A last having a heel part, a toe part and a connecting plate between them, the heel and toe parts being separated by a transversely extending saw cut that extends

from the top to the bottom of the last and each part being provided with a slot for receiving the connecting plate, one of said parts also being cut away so that there is a wedge shaped opening in the upper portion of the last whereby the heel part can be moved upwardly and forwardly relative to the toe part, said plate being rigidly secured to one of said parts by rivets and to the other of said parts by rivets which enter slots that are provided in said plate, one of said parts having therein a compression spring that engages a nose or projection which is also provided on said plate whereby the heel part and toe part will be normally maintained in an extended position relative to each other, the slots and pins passing therethrough being constructed and arranged so that the lower forward portion of the heel part will engage and abut against the lower rear portion of the toe part and in such manner that the lower surface of the heel part and of the toe part will be in effect continuations of each other due to the rivets in the slots striking the plate.

3. A last having a heel part and a toe part connected together by a longitudinally and vertically extending plate that is rigidly secured to said toe part by horizontally extending rivets or pins, said plate having slots and a projection, the heel part having upper and lower pins or rivets that pass through said slots and a spring which presses upwardly against said projection to maintain the heel part in extended position relative to the toe part, the slots being arranged in such manner that the upper rivet or pin will both rise and approach the toe part as the heel part is moved upwardly from unbroken or extended position to broken or shortened position.

4. A last having a toe part and a heel part each provided with a vertically and longitudinally extending saw cut, the heel part also having rivets or pins, a connecting plate located in said cuts, said plate being rigidly secured to the toe part, being provided with slots through which pass rivets or pins that are comprised in the heel part and also with a rearwardly extending projection or nose which is engaged by a compression spring means which is provided in the heel part for maintaining the heel and toe parts in extended position.

5. A last comprising a toe part, a heel part movable relative to the toe part, and a vertically and longitudinally extending connecting plate that is slotted to receive pins or rivets in the heel part and that is provided with a projection or nose, said plate being rigidly connected to the toe part, the heel part comprising rivets or pins that pass through said slotted portions of the plate, thus securing the heel part to the toe part in a manner to permit relative move-

ment between said parts, the heel part comprising a metal heel plate which is secured to the lower portion of the heel part, said heel part also being provided with an upwardly extending bored opening, a compression spring means located in said opening, a plug in said opening against which one end of the spring means rests, the other end of the spring means being engaged 10 with the nose or projection on the vertically

and longitudinally extending plate, the heel plate being arranged so that it covers the plugged opening and also serves as a resting member for the plug:

This specification signed and witnessed 15 this 9th day of February, A. D., 1914.

GEORGE CLAUSING.
